UNITED STATES PATENT OFFICE.

ANTOINE J. LANGEIER, OF PROVIDENCE, RHODE ISLAND.

HEEL-MACHINE.

SPECIFICATION forming part of Letters Patent No. 317,149, dated May 5, 1885.

Application filed July 7, 1884. (No model.)

To all whom it may concern:

Be it known that I, ANTOINE J. LANGEIER, of Providence, in the State of Rhode Island, have invented a new and useful Improvement 5 in Heel-Machines, of which the following is a specification.

My invention relates to machines for cutting out the leather blanks and cementing a sufficient number of such blanks together to form 10 the heel of a boot or shoe; and it consists in improved devices for cutting out the heel-blanks and for applying paste or cement to the same, and also in the combination of cutting and paste-applying devices and intermittently-revolving carriers, with means for discharging the heel-blanks from the receiving-openings of one of the revolving carriers into the corresponding chamber of the opposite carrier, and for compressing the accumulated 15 contents of such chamber, and means for discharging the heels so formed and compressed from the chamber of the carrier, and also in certain improved mechanical devices adapted for the successful operation of the various parts of the 20 machine.

Figure 1 represents a front elevation of the machine. Fig. 2 is an elevation of the left-hand side of the machine. Fig. 3 is a rear elevation of the same. Fig. 4 is a detail section 25 showing the mechanism of the revolving carriers and the heel-blank cutters, the cross-barred plunger at one of the chambers of the delivering carrier-wheel being broken away to more plainly show the cross-grooves in which it is made to operate. Figs. 5 and 6 are detail views of the sliding head for operating the cutting-plunger and the paste-applying force. Fig. 7 is an end elevation of the clamping-piece which serves to secure the cutting-plunger to the adjustable shoe of the sliding head. 30 Figs. 8 and 9 are detail views of the clutch mechanism for stopping and starting the machine. Figs. 10, 11, 12, and 13 are detail views of the cutting-plunger, the pasting-force, and the inwardly-projecting guide-plates of the chambered wheel adapted to receive the blanks for the smaller portion of the heel. Figs. 14, 15, and 16 are detail views of the mechanism adapted to force the accumulated 35 smaller blanks from the receiving-openings of one of the revolving carriers into the receiving-chamber of the opposite carrier.

Figs. 17 and 18 are detail views of the barred plunger adapted for delivering the completed heel from the chamber in which it is formed. 55 Fig. 19 shows an end elevation of the adjustable shoe which serves to hold the cutting-plunger. Fig. 20 represents a horizontal section of the lower end of the sliding head, taken in the line *x x* of Fig. 19. Fig. 21 represents 60 a vertical section of the sliding head and shoe, taken in the line *y y* of Fig. 20. Fig. 22 represents a horizontal section of the holding-shoe, taken in the line *z z* of Fig. 21.

In the accompanying drawings, A represents the supporting-frame of the machine; B, the table, in which the heel-blank cutters C C' are securely held by means of the cutter-holders D D', which are secured to the table B by means of the screws *a a*, the heads of 65 which are cut away at one side of the screw, in order that the cutter-holder may be released from the table upon the semi-revolution of the screw, the projecting side of the head of the same being made to pass into the 70 segmental recesses *b b*, made in the opposite edges of the cutter-holders, as shown in Fig. 4.

To the upward extension of the frame A, which branches laterally in opposite directions, are secured the sliding heads E E', to 80 which an up-and-down movement is imparted by means of the shaft F, at the opposite ends of which are formed wrist-pins *c*, each held in a horizontally-sliding box, *d*, which moves back and forth within the slot-opening *e* when 85 imparting an up-and-down movement to the sliding heads, as shown in Figs. 5 and 6; and the shaft F is driven from the shaft F' by means of the bevel-gears G' G'.

To the under side of the outwardly-projecting lip *f* of the sliding head is secured the holding-shoe G, which is made capable of slight adjustment relatively to the sliding head by means of the opposite gibs, *g g*, made in wedge form, and operated for the purpose of 90 tightening the shoe within the transverse groove of the sliding head, or for adjustment therein by means of the screws *h h*, (shown in section in Fig. 5,) the heads of the screws being provided with an annular groove, *i*, adapted to receive the open slotted head *j* of the tapering gibs *g*, as shown in Fig. 6. Upon drawing back the wedge-formed gibs *g g*, by 95 means of the screws *h h*, the holding-shoe G

may be readily placed in any required position between the gibbs, and thereafter, by screwing up on one of the wedge-formed gibbs and unscrewing the other, the proper lateral adjustment of the holding-shoe will be effected, and the same means will serve to firmly lock the holding-shoe in its proper position relatively to the cutting-die and sliding head. At the under side of the holding-shoe G is formed an undercut groove, k, the forward end of which is made in circular form, and adapted to receive the conically-enlarged head l of the hollow shank r of the cutting-plunger H, which is securely held within the groove k by means of the clamping-piece m, which is conically hollowed to fit the rear side of the head l. The clamping-piece m is made to fit the inclined sides of the groove k, and is operated to clamp the shank r by means of the screw o, provided at its head with a circumferential groove, p, within which is held the notched lug q, which extends upward at the rear end of the clamping-piece, so that the forward or backward movement of the screw will be immediately imparted to the clamping-piece m.

Upon the lower end of the hollow shank r is screwed the cutting-plunger H, (shown in section in Figs. 10 and 11,) which is made in the form of a heel, as shown in Fig. 12, the plunger H being made to screw against a shoulder, s, and loosely upon the shank r, and over the plunger H, is placed the holder I, made to fit the cylindrical exterior of the shank r, and also the sides of the plunger H, as shown in Fig. 12, and between the holder I and the lower face of the holding-shoe G is placed the spiral spring J, which operates to press the inwardly-directed flange of the holder I against the upper side of the plunger H, as shown in Fig. 10. The shank r is bored out to receive the sliding paste tube and force K, to the lower end of which is secured the valve-holder L.

The valve u, which rests upon the conical valve-seat t, is provided with a guiding-stem, v, upon which is placed the downwardly-acting spring w, and at the lower side of the valve u is placed the projecting pin or stud x, by means of which the valve will be raised from its seat, so as to allow the proper quantity of paste to flow onto the upper surface of the leather blank when the same is under the action of the cutting or forcing plunger.

The valve-holder L is provided with a flange, y, which is adapted to rest against the shoulder z at the lower end of the hollow cylindrical shank r, the flange y, which is also provided at its lower side with the clearing-recesses a⁵, being held against the shoulder z by means of the spiral spring a⁴, which encircles the tube K above the shoe G, and is held between the shoe and the collar b', above which the tube K is deflected for a short distance, and connected with one of the outlet-pipes c' of the paste-cup M by means of a flexible tube, d', which is shown broken away in the drawings. The tube K at the initial point of deflection is pro-

vided with a lug, c', made with a hollow recess, f', at its upper surface, into which the rounded end g' of the lever N is made to rest. The lever N is pivoted to the sliding heads E and E' at the point h', and from the outer short arm of the lever N connection is made to the parallel lever O by means of the link i'. The lever O is pivoted to the sliding head at the point j', and at the point k' on the lever O a pivoted connection is made to the spring-box P, within which is placed the bolt l', provided with a head, m', between which and the closed upper end of the box P is placed the spiral spring n', which is to be made more rigid than the spring a', which encircles the tube K. The bolt l' is provided with a screw-thread, o', upon which is placed the sleeve-nut p', having a milled head, q', and the sleeve-nut p' is made to loosely fit the bore of the projecting lug r', which extends outward from the upper end of the frame A.

Below the table B, in the vertical plane of the cutting mechanism, are placed the intermittently-revolving carrier-wheels QQ', which in this instance are arranged to revolve in opposite directions, the adjacent peripheries of the wheels being made to nearly touch each other, and also being provided with the interlocking gears s' s², by means of which an equal simultaneous movement will be imparted to the carriers, the adjacent peripheries of the carriers passing within the vertical slot-opening x' in the frame A. The carrier-wheel Q is secured to the front end of a hollow sleeve, R, loosely held in the journal-box S', the projecting rear end of the sleeve being provided with four clutch-spurs, c², which are adapted to engage with the sliding clutch d², arranged upon the shaft T, which passes through the bore of the sleeve R, and the carrier-wheel Q' is placed loosely upon the fixed stud t', which is firmly held in the stand u', secured to the side of the frame A at the front edge of the slot x', (shown in Fig. 2,) and to either the stand u' or the stud t' is firmly secured the fixed cam v'. The rim m² of the carrier-wheel Q is provided with four circular axially-directed openings, U, one of which is clearly shown in Fig. 2, and at the edges of the same are secured the inwardly-projecting guiding-plates n², made of sheet-steel, and provided with the inwardly-projecting lip n³, as shown in Fig. 4, which serves to support the deposited heel-blanks, the back portion of the sheet-steel guiding-plates being provided with the attached cylindrical holding-pieces n⁴, which enter the holes o² made in the rim of the wheel Q at a slight distance from the edge of the circular opening, as shown enlarged in Fig. 13, a narrow slit, p², adapted to receive the thin guiding-plate n², being made from the holes o² to the openings U, the edges n⁵ being made to closely embrace the edges of the heel-blanks, as shown by the dotted lines. To the side of the frame A, at the front edge of the slot x', is also secured the slide Z, adapted to receiving the sliding head

S, which is provided with a vertical slot a^2 , within which is placed the sliding box b^2 , adapted to receive the wrist-pin c^3 of the operating-crank at the forward end of the shaft 5 T, which extends through the bore of the sleeve R to a point within the hollow of the carrier-wheel Q. The sliding head S is provided with a projecing shank, e^2 , upon the extension of which is cut the screw-thread f^2 , and the shank 10 e^2 is bored out to receive the shaft g^2 , at the forward end of which is secured the cam-wheel h^2 , provided at its face with three or more inclined spurs, j^2 . The plunger-head V is provided with a recess, q^2 , adapted to receive the 15 cam-wheel h^2 , and is adjustably secured to the shank e^2 by means of the double-threaded sleeve r^2 and check-nut s^2 , the screw-thread at the inner portion of the sleeve r^2 being made to fit the right-hand screw-thread upon the exterior of the shank e^2 , and the screw-thread upon the outer portion of the sleeve being made the reverse of the thread upon the inner portion thereof, so as to fit the left-hand thread made 20 within the cavity of the plunger-head V, so that by turning the sleeve r^2 the plunger-head V may be either projected forward or retracted, as desired. Within the cavity of the plunger-head, and at the back of the cam-wheel h^2 , is placed the ring t^2 , which serves to 25 support the cam-wheel when the cams j^2 are acting against the heads w^2 of the clearing-pins v^2 , which are retracted by means of spiral springs u^2 , which encircle the clearing-pins. The small forward ends of the clearing-pins 30 are made to project from the orifices $x^2 x^3 x^4$, made in the face of the plunger-head, and the face and edge of the plunger-head V are provided with narrow grooves y^2 , adapted to receive the sheet-steel guiding-pieces n^2 of the 35 carrier-wheel Q.

Upon the rear end of the shaft g^2 , and within the slot z^2 , made in the sliding-head S, is placed the outwardly-projecting finger a^3 , and to the face of the sliding box b^2 is secured the 40 arm b^3 , which, upon the downward movement of the sliding box by the action of the wrist-pin c^3 , will cause an angular movement of the finger a^3 and the cam-wheel h^2 , thus causing the outward projection of the clearing-pins v^2 , and as the sliding box b^2 continues downward 45 the finger a^3 will be carried behind the downwardly-extended end of the arm b^3 , which thus serves to limit the angular movement imparted to the cam-wheel h^2 . The back side of the 50 hub of the finger-piece a^3 is flattened, as shown by the dotted lines in Figs. 14 and 15, and to the back side of the sliding head S is attached the spring x^3 , provided with an elongated face, y^3 , adapted to press against the flat surface z^3 , 55 formed at the back of the finger-piece, and thus serving to hold the cam-wheel h^2 normally in the position relatively to the clearing-pins v^2 , (shown in Fig. 4,) which shows the arm b^3 at the time of its initial action upon the projecting end of the finger a^3 for imparting the 60 desired angular movement to the cam-wheel h^2 . A sectional view of the sliding head, show-

ing the position of the finger-piece a^3 and its accessories at the time of the initial movement of the finger, is shown in Fig. 15, and the relative position of the pins at the completed downward movement of the sliding box b^2 is shown in Fig. 14, the spring x^3 being in this case elevated by the action of the projecting corner of the finger-piece, and upon the upward movement of the sliding box to the medium position (shown in Fig. 15) the finger a^3 will have become released from the action of the arm b^3 , and the cam-wheel h^2 will have been brought, by means of the action of the spring x^3 , back to its normal position, as shown in Fig. 4. The supporting-ring t^2 is firmly held in position within the cavity of the plunger-head by means of the screw d^3 . The carrier-wheel Q' is provided with the four chambers 70 U', bored out at their rear to receive the shanks e^3 of the clearers f^3 , which are formed of the cross-bars $g^3 g^3$, let into the forward end of the shanks e^3 , and at the back of the cross-bars are placed the cylindrical blocks h^3 , provided 75 with cross-grooves i^3 , adapted to receive the cross-bars g^3 , so that when fully within the grooves i^3 the forward edge of the cross-bars may lie in the plane of the front surface of the blocks h^3 . At the rear end of the shanks e^3 are placed the collars j^3 , and between the collars j^3 and the shoulder k^3 are placed the spiral 80 springs l^3 , which serve to hold the rear ends of the shanks e^3 against the periphery of the fixed cam v^1 . The carrier-wheel Q' is also provided with sheet-steel guiding-plates n^2 , as in the case of the carrier-wheel Q, hereinbefore described; but the guiding-pieces n^2 are in this case made without the projecting lip n^3 , and extend to the upper face of the cylindrical 85 blocks h^3 , which are to be firmly held within the chambers U' by suitable means. The driving-pulley W is held upon a stud at the back of the frame A, the shaft F' being driven from the pulley W by means of the gear m^3 , secured 90 to the hub of the pulley, and the gear n^6 upon the rear end of the shaft F'. The loose gear o^3 upon the shaft T is connected with the gear m^3 upon the pulley W by means of the intermediate gear, m^5 , and at the side of the gear o^3 upon the shaft T is secured the cam p^3 , the 95 resting portion q^3 of the cam-groove being made to extend through ninety degrees of the periphery of the cam, and below the shaft T and parallel therewith is placed the sliding 100 rod r^3 , upon which is secured the clutch-fork s^3 , and between the hub of the clutch-fork and the shoulder t^3 is placed the spiral spring u^3 .

Upon the head v^3 at the outer end of the sliding rod r^3 is placed the pin w^3 , adapted to 105 enter the cam-groove q^3 , which serves to operate the clutch d^2 . The outer side of the loosely-revolving gear o^3 is provided with the clutch-teeth x^3 , adapted to engage with the similar teeth of the sliding clutch y^3 , which is 110 operated for engagement with the clutch-teeth x^3 by means of the pivoted pedal z^3 , which is connected to the sliding clutch y^3 by means of the connecting-bar a^4 , arm b^4 , secured to one

end of the rocking shaft c^4 , upright arm d^4 , secured to the opposite end of the shaft c^4 , and the pivoted shoe e^4 , which enters the circumferential groove f^4 of the sliding clutch.

5 In order that the clutch y^3 may be automatically disengaged at each complete revolution of the shaft T , I provide at the rear of the sliding clutch y^3 a flange, g^4 , provided at its forward face with an inclined spur, h^4 , and to the projecting bracket i^4 is secured the holding-piece j^4 , provided at its upper end with the parallel upright guides k^4 , which serve to guide the under-beveled head l^4 of the sliding bolt m^4 , which is forced downward within the holder j^4 by means of the spiral spring o^4 , which acts against the shoulder p^4 at the upper end of the bore of the holder and the upper end of the adjustable screw-sleeve q^4 at the lower end of the bolt.

20 In order to prevent the untimely removal of the clutch from engagement with the catch-spur of the loose gear o^3 , I secure a fixed pin, r^4 , to the attaching-base s^4 of the holder j^4 , in such a position relatively to the flange g^4 that when the clutch is in proper engagement the flange g^4 will revolve immediately in front of the fixed pin r^4 , and at the place of the automatic disengagement of the clutch I cut a notch, t^4 , in the edge of the flange g^4 and bevel 25 the back edge of the flange beyond the notch t^4 , as shown in Figs. 8 and 9. The bevel u^4 serves to insure the complete closure of the clutch upon again throwing the clutch-sleeve forward by means of the pedal z^3 .

35 Upon the side of the spring-box P is secured the spring-bell Y , from the operating-lever v^4 of which connection is made to the arm w^4 by means of the link x^4 , which is provided at its upper end with the adjustable thumb-nut y^4 , 40 the arm being fixedly attached to the bolt l^4 .

In operating the machine the leather is to be fed under the cutting-plungers at each side of the bed B , the cutter C' being made slightly larger than the cutter C , thus producing heel-blanks of unequal sizes, the blanks formed by the larger cutter being adapted for the upper portion of a heel, while the smaller blanks are to be attached thereto, so as to form the lower portion. The reciprocating movement 45 imparted to the slides $E E'$ will first cause the holder I to be brought down upon the upper surface of the leather strip A' , Fig. 10, thus clamping it firmly around the upwardly-projecting edge of the cutter; and during the continued downward movement of the sliding head the holder I will be firmly pressed against the leather at the outside of the cutter by means of the spiral spring J . The downward movement 50 of the cutting-plunger, which is made to closely fit the hollow of the cutter, will cause the separation of a heel-blank from the leather strip, and the pasting-forcer, which, after the cutting of the heel-blank, has, by reason of the multiplying action of the levers $N O$, a more extended downward movement 55 than that of the cutting-plunger, will serve to carry the heel-blank A' downward into the

carrier-opening U between the adjacent edges of the guiding-plates n^2 , as shown in Fig. 11, the heel-blank first deposited resting in contact with the upper edge of the projecting lips n^3 , as shown in the figure, and upon the contact of the pasting-forcer with the surface of the heel-blank the valve u will be raised from its seat t , thus opening a passage for the free flow of paste or cement from the paste-cup M , and upon the continued reciprocation of the sliding heads of the machine an equal number of superposed heel-blanks having a deposit of paste between them will be deposited in the radial opening U of the carrier Q and in the chamber U' of the carrier Q' , 70 the spring-controlled pasting-forcer K being caused to make a gradually-decreasing downward movement, by reason of the accumulated 75 obstruction caused by the deposited heel-blanks, until at a certain downward movement of the forcer the lever v^4 will be so acted upon by the arm w^4 and link x^4 as to cause the bell to ring, thus notifying the operator 80 that the proper number of heel-blanks have been cut and deposited in the carriers, upon which notification he ceases to feed the leather to the cutters, and by means of the pedal z^3 effects the proper engagement of the clutch y^3 85 with the clutch-spurs x^3 at the side of the loosely-revolving gear o^3 , which engagement will cause the shaft T to make one complete revolution, the clutch y^3 becoming automatically disengaged at the exact completion of a 90 single revolution by reason of the contact of the inclined spur h^4 of the flange g^4 against the inclined face m^6 of the head l^4 of the spring-bolt m^4 , which upon the initial contact will be raised within its holder j^4 until the milled 95 head of the adjusting-sleeve q^4 brings up against the lower end of the holder, thus causing the forcible disengagement of the clutch, whereupon the bolt m^4 will be brought immediately back to its normal position, as shown 100 in Fig. 2, by means of the spring o^4 , which surrounds the bolt m^4 within the holder, thus leaving the clutch y^3 in a position for ready 105 re-engagement subsequent to the renewed action of the cutters $C C'$. The engagement of 110 the clutch y^3 , by causing a single revolution of the shaft T , will also cause the corresponding 115 revolution of the cam p^3 , which is so arranged relatively to the movement of the shaft F , which operates the sliding heads, that the portion q^3 of the cam-groove, which serves to hold the clutch d^2 in engagement with the clutch-spurs c^2 of the sleeve R , to which the carrier Q is 120 attached, will be in operative engagement only when the forcer K is elevated above the openings or chambers of the carriers, thus allowing the carriers Q and Q' to be moved through a space of ninety degrees, at the completion of which movement the clutch d^2 will 125 become disengaged by the action of the cam-groove q^3 , the quarter-revolution of the carriers serving to bring a new opening and chamber under the cutters $C C'$, and also to bring 130 the opening and chamber previously filled 135

with heel-blanks to an adjacent position preparatory to the action of the plunger V, the forward movement of which serves to force the accumulation of smaller heel-blanks in the 5 opening U from the said opening into forcible contact with the accumulation of larger heel-blanks in the chamber U' of the carrier Q, and upon the retrograde movement of the plunger V, the clearing-pins v², which are 10 projected from the face of the plunger by the action of the cam-wheel h², as hereinbefore described, will serve to prevent the accumulated compressed heel-blanks from following the plunger V in its backward movement, and 15 upon the continued action of the machine the accumulated heel-blanks in the chamber U' will be brought to the lower portion of the carrier Q' and will be discharged therefrom by the action of the discharging-forcer f³ and 20 fixed cam v.

The opening U in the carrier Q is provided at one side with the projecting lip or spur u⁵, and the direct forward movement of the plunger V and the angular movement of the carrier Q are to be so timed relatively to each other that the lip u⁵ will bring up against the moving forward end of the plunger, thus forming a stop to properly limit the forward movement of the carriers.

30 The machine may be readily adapted for making heels of various sizes by changing the guiding-plates n², and correspondingly changing the cutters and cutting-plungers, and in forming low heels a single cutter at either side 35 of the machine may be used, the accumulated cemented heel-blanks being discharged from the chamber of the carrier, as before. It will also be readily seen that the relative movement of the carrier Q may be reversed; but 40 the operative arrangement of the carriers as shown and described is preferred, and various devices may be employed to impart an increased variable movement to the forcer, which serves to carry the heel-blanks through 45 the hollow of the cutter and into the receiving-carriers.

The screw-sleeve p' upon the bolt l', which moves up and down with the sliding head, is to be so adjusted relatively to the movement 50 of the cutting-plunger that immediately upon the separation of the heel-blank A² from the leather strip A', by the conjoint action of the cutter C and cutting-plunger H, the milled head q' shall bring up against the upper surface of the projecting lug r', and upon the 55 continued downward movement of the sliding head the outer end of the lever N will be caused to rise relatively to the sliding head, and this upward movement will be imparted to the lever N by means of the link i', thus causing an increased downward movement at the end g' of the lever N, and the increased downward movement of the end g' of the lever, which rests upon the projecting lug e', will 60 cause the desired increased movement of the forcer K in opposition to the upward action of the comparatively-weak spring a', so that

while the cutting-plunger will have been moving downward to the position relatively to the cutter C shown in Fig. 11, the forcer K will 70 have been carried downward to the position within the opening U of the carrier-wheel, shown in the same figure, the forcer being operated in this case without causing the compression of the comparatively stiff spring n' 75 in the box P; but upon the subsequent reciprocation of the sliding head, and the resulting formation of an additional heel-blank, the forcer K will be allowed to have a restricted downward movement by reason of the resulting compression of the spring n', which compression will be correspondingly increased at 80 each reciprocation of the sliding head until a sufficient number of heel-blanks have been deposited upon the guiding-plates in the opening U of the carrier-wheel Q. 85

I claim as my invention—

1. The combination of the two stationary heel-shaped cutters of different sizes and the operatively-connected carriers adapted to receive the heel-blanks from the cutters, with means for intermittently revolving the carriers, and means for forcing the heel-blanks continuously through the cavity of the cutters and into the receiving openings or chambers of the carriers, substantially as and for the purpose specified. 90

2. The combination of the intermittently-revolving carriers having radial openings or chambers adapted for the reception of heel-blanks of different sizes, with means, substantially as described, for forcing the accumulated smaller heel-blanks in the receiving-opening of one of the carriers into forcible connection with the accumulated larger heel-blanks in the corresponding chamber of the opposite carrier, substantially as described. 105

3. The combination of the intermittently-revolving carriers adapted for heel-blanks of unequal size, with means, substantially as described, for forcing the accumulated smaller heel-blanks in the receiving-opening of one of the carriers into forcible connection with the accumulated larger heel-blanks in the corresponding chamber of the opposite carrier, 115 and means for discharging the combined blanks from the carrier, substantially as described. 110

4. The combination of the revolving carrier provided with radial receiving-openings with the inwardly-directed guiding-plates provided with an inwardly-projecting lip adapted to support the deposited heel-blanks, substantially as described. 120

5. In a heel-machine, the combination of a carrier provided with radial receiving-openings, and means, substantially as described, for intermittently revolving the carrier, with the inwardly-directed guiding-plates provided with a projecting lip adapted to support the deposited heel-blanks, and a discharging-plunger provided with grooved openings in its face and edge adapted to receive the inwardly-directed guiding-plates, and thus permitting the proper forward movement of 125 130

the discharging-plunger, substantially as described.

6. In a heel-machine, the combination of a carrier provided with radial receiving-openings, and means, substantially as described, for intermittently revolving the carrier, with the inwardly-directed guiding-plates provided with a projecting lip adapted to support the deposited heel-blanks, and a discharging-plunger provided with grooved openings on its face and edge adapted to receive the inwardly-directed guiding-plates, and with automatically-operated clearing-pins for preventing the adhesion of the heel-blanks to the face of the plunger, substantially as described.

7. In a heel-machine, the combination of a carrier provided with radial receiving-chambers, and means, substantially as described, for intermittently revolving the same, the inwardly-directed guiding-plates and grooved pressure-block within the chamber of the carrier, with the barred forcer, adapted to enter the grooves of the pressure-block, and means of operating the forcer for the purpose of receiving and discharging the heel-blanks, substantially as described.

8. In a heel-machine, the combination of a carrier provided with radial receiving-openings and inwardly-directed guiding-plates having a projecting lip, a discharging and pressing plunger grooved on its face and edge to receive the guiding-plates, and means, substantially as described, for operating the discharging and pressing plunger, with an opposite carrier provided with radial receiving-chambers, inwardly-directed guiding-plates, grooved pressure-blocks, barred forcers, means for operating the same, and means for imparting a simultaneous and equal movement to the opposite carriers, substantially as and for the purpose specified.

9. In a heel-machine, the combination of the stationary hollow cutter, the reciprocating cutting-plunger adapted to pass within the hollow of the cutter, and the spring-operated holder inclosing the cutting-plunger and adapted to hold the leather firmly around the edge of the cutter, substantially as described.

10. In a heel-machine, the combination of the intermittently-revolving carrier provided with radial receiving openings or chambers, the stationary hollow cutter, the hollow reciprocating cutting-plunger, and the spring-controlled forcer operating within the hollow of the cutting-plunger, and serving to carry the heel-blanks through the stationary hollow cut-

ter and to deposit the same in the radial receiving openings or chambers of the carrier, substantially as described.

11. In a heel-machine, the combination of the stationary hollow cutter, the reciprocating cutting-plunger, and the hollow paste-carrying forcer, adapted to carry the heel-blanks through the hollow cutter and to apply paste or cement to the upper side of the blank, substantially as described.

12. In a heel-machine, the combination of the stationary hollow cutter, the reciprocating cutting-plunger, and the tubular forcer adapted to force the heel-blanks through the hollow of the cutter and provided with a valve having a projecting stem, whereby, upon the forcible contact of the valve-stem with the upper surface of the leather, the paste or cement will be caused to flow from the valved orifice of the tubular forcer, substantially as described.

13. In a heel-machine, the combination of the stationary hollow cutter, the reciprocating plunger, the paste-supplying forcer, and a spring adapted to hold the paste-supplying forcer against a shoulder or stop while the face of the cutting-plunger is above the edge of the cutter, substantially as described.

14. In a heel-machine, the combination of the stationary hollow cutter, the sliding head, cutting-plunger, paste-supplying forcer, and the spring adapted to hold the paste-supplying forcer against a shoulder or stop while the face of the cutting-plunger is above the edge of the cutter, with the spring-box, the inclosed spring, the bolt provided with an adjustable stop, and a multiplying connection between the spring-box and the paste-supplying forcer, whereby, upon the downward movement of the face of the cutting-plunger below the edge of the cutter, a variable increased movement will be imparted to the forcer, substantially as described.

15. In a heel-machine, the combination of the clutch operatively connected to the pedal and having a projecting flange provided with a disengaging-spur and a notch, and the fixed pin adapted to enter the notch and to prevent the untimely disengagement of the clutch with the spring-operated bolt having a head beveled on the side adjacent to the flange of the clutch and adapted for engagement with the disengaging-spur of the flange, substantially as and for the purpose specified.
